SIGN

John W. Linley, Jr., Anderson, S. C.

Application February 25, 1949, Serial No. 1,090

Term of patent 14 years

(Cl. D1—12)

To all whom it may concern:

Be it known that I, John W. Linley, Jr., a citizen of the United States, residing at Anderson, in the county of Anderson and State of South Carolina, have invented a new, original, and ornamental Design for Sign, of which the following is a specification, reference being had to the accompanying drawing, forming a part thereof.

I claim:

The ornamental design for a sign, substantially as shown.

JOHN W. LINLEY, JR.
